JONAS NORTHROP, OF HOPEDALE, MASSACHUSETTS, ASSIGNOR, BY MESNE ASSIGNMENTS, TO DRAPER CORPORATION, OF HOPEDALE, MASSACHUSETTS, A CORPORATION OF MAINE.

LET-OFF MECHANISM.

Application filed February 11, 1927. Serial No. 167,504

The present invention relates to an improvement in let-offs for looms.

The object of the invention is to reorganize and improve the construction of let-offs, and to this end the invention consists in the let-off hereinafter described and particularly defined in the claims.

In the accompanying drawing illustrating the preferred form of the invention, Fig. 1 is an end elevation of a loom provided with the let-off of the present invention; Fig. 2 is a back view of a portion of the loom showing the mechanism; Fig. 3 is an enlarged end elevation of a portion of the loom shown in Fig. 1; and Fig. 4 is a detail of the ratchet and pawl devices.

The illustrated embodiment of the invention is described as follows: The frame 1 of the loom carries the various parts including the swords 2, the lay 3, the pitman 4, the crankshaft 5, etc. The warp beam 6 is supported on the warp beam bracket 7 secured to the rear of the loom frame. This warp beam bracket carries a vertical bracket 8, which at its upper end is braced to the frame by the members 10, and carries the whip roll 11 mounted on the whip roll arm 12, carried by the whip roll shaft 13, which is pivotally supported in the bracket 8. To the whip roll shaft is attached the let-off control arm 14. A whip roll spring 15 embracing the rod 16 is mounted at its left hand end to slide in the support 17 and pivotally attached at its other end 18 to the whip roll control arm 14, and affords means for yieldingly pressing against the control arm to support the whip roll in proper position. The tension of the spring may be adjusted by the adjusting and check nuts 20 in the usual manner. The whip roll control arm carries at its lower end the bar 21 which extends from the arm to the front of the loom, being received at the front between the forks 22 of the guide bracket 23. The bar 21 is pivotally attached at 24 to the lower end of the whip roll arm, and may be adjusted upon this pivot to occupy different positions with respect to the whip roll control arm 14. The lower end of the whip roll arm is extended beyond the pivot point 24 to the left, as shown in Fig. 1, and there provided with a slot 25 which receives a bolt 26 passing through a second slot 27 in the bar 21. By loosening the nut on the bolt 26, the bar may

be adjusted in angular position with respect to the whip roll, and then by tightening the nut the bar may be secured rigidly to the whip roll control arm. To the front end of the bar 21 is pivotally attached the rod 28, which is bent back upon itself at its upper end to embrace a pin 30, which is secured in the arm 31 of the pawl carrying bell crank lever 32. The other arm 33 of the bell crank lever carries the pawl 34, which is adapted to engage the ratchet wheel 35 secured upon the worm shaft 36, which extends diagonally downward from the front of the machine to the rear thereof, being supported in suitable bearings in the bracket 37 at the front of the machine and the bracket 38 at the rear of the machine. Upon the rear end of the worm shaft is secured the worm 40, which engages the worm wheel 41 on the warp beam. Actuation of the ratchet wheel by the pawl turns the warp beam to let-off or let-back the warp, which extends upward from the beam over the whip roll 11 through the harnesses over the breast roll 42 and thence to the take-up roll 43.

The bell crank pawl carrying lever 32 which rotates the worm shaft is actuated by means of a connection with the lay. To the lay shaft 44 is secured the arm 45 which projects forwardly from the lay shaft beyond the front of the machine where a bolt 46 forms a pivot for the pawl actuating rod 47, which extends upwardly to the slide head 48 at the upper end of the rod. This head 48 is adjustably secured to the rod by means of the nuts 50 which are threaded on the rod and hold the head 48 in adjusted position thereon. This head 48 is provided with a slot 51 which embraces the pin 30 in the arm 31 of the bell crank lever 32. Upon each beat of the lay the pawl actuating rod 47 is raised and lowered, and the pawl is thereby actuated to advance the worm shaft to feed the warp providing the control rod 28 is in such position as to permit the bell crank lever to rise. When the control rod 28 is lowered, it prevents the bell crank lever from moving to the right, as shown in Fig. 4, and then the reciprocations of the actuating rod 47 will be ineffective to actuate the bell crank lever. But when the control rod 28 is raised, the bell crank lever will be actuated by the actuating rod 47. A spring 52 is employed normally tending to turn the bell

crank lever 32 in the direction to turn the latter to the right, as seen in Fig. 4, but the control rod 28 may prevent such turning movement when it is depressed, that is to say, when the whip roll occupies a higher position than normal.

The front end of the worm shaft is provided with a hand wheel 53 by which the operator standing at the front of the machine may turn the worm shaft by hand, either in the direction to let-off more warp by turning it to the right, as viewed from the front of the machine, or by lifting the pawl by pressure upon its tail 54 by the thumb while turning the wheel with the same hand to the left, as viewed from the front of the machine.

The general operation of the mechanism is not dis-similar to the operation of let-offs heretofore employed in the art. When the warp is too tight, it depresses the whip roll which thereby causes the control rod 28 to be raised so as to permit the actuation of the worm shaft by the lay to cause the latter to rotate the warp beam to let-off the warp. When the warp tension diminishes below a predetermined amount, the whip roll will rise slightly and the control rod 28 will be pulled downwardly so as to prevent returning movement of the pawl, whereupon the feed of the warp from the beam will be suspended. From time to time the feed will be suspended in the operation of the loom.

In weaving, when the operator has a "pick out" he is required in constructions of let-off mechanism heretofore employed, to go to the rear of the loom and to loosen the warp by manual manipulation of the let-off, and also tighten it again after the pick out is completed. The present invention is of great advantage over this construction because it enables the operative to release the warp tension and to re-apply it again without going to the back of the machine.

The present construction is of advantage because the let-off is operated to feed the warp without much improvement of the whip roll, as in prior positive let-off mechanism, wherein, upon each movement of the pawl to move the ratchet forward, the whip roll was oscillated in both directions. Furthermore, it has been found in actual practice that this let-off improves the quality of the cloth.

Having thus described the invention, what is claimed is:

1. A let-off mechanism for looms having, in combination, a loom frame, warp supporting means, gearing connected therewith, a shaft connecting with the gearing extending from the lower back part of the loom to the upper front part of the loom and adapted to be rotated manually from the front of the loom, a ratchet and pawl mechanism for actuating the shaft and including a pawl car-

rier mounted for rocking movement, a spring for moving the pawl carrier in one direction, a connection between the pawl carrier and lay for moving the pawl carrier in the opposite direction, a whip roll supported for movement in response to variations in the tension of the warp, and means controlled by the movement of said whip roll to vary the stroke of said pawl carrier to thereby vary the feeding of the warp by the warp beam.

2. A let-off mechanism for looms having, in combination, a warp beam, actuating means therefor including gearing, a shaft connected with the gearing mounted on the loom and extending from the rear of the loom to the front thereof and adapted to be rotated manually from the front of the loom, a ratchet secured to said shaft at the front of the loom, a pawl carrier mounted adjacent said ratchet, a pawl on the pawl carrier to rotate the ratchet and adapted to be manually held out of engagement with the ratchet, a whip roll, a whip roll control arm secured to the whip roll, and an arm extended from the control arm to the forward part of the loom and connected with the pawl actuating means for the shaft for controlling the actuation thereof.

3. A let-off for looms having, in combination, warp supporting means at the rear of the loom, gearing connected therewith, a shaft for actuating the gearing extending from the rear to the front of the loom and adapted to be rotated manually from the front of the loom, ratchet and pawl mechanism at the front of the loom provided with driving means for moving the pawl in actuating direction and a spring for retracting the pawl to initial position, a whip roll, and connections therebetween and the pawl to prevent the spring from retracting the pawl as long as the warp tension is greater than a predetermined amount.

4. A let-off for looms, comprising in combination, a warp beam, a shaft for rotating the warp beam and extending to the front of the loom and adapted to be operated manually from the front of the loom, means for rotating said shaft from a going portion of the loom including a ratchet disposed at the front of the loom, a pawl adapted to engage and rotate the ratchet, a pawl carrier mounted for rocking movement to actuate the pawl, means for rocking the pawl carrier, a whip roll supported for movement in response to variations in the tension of the warp, and connections between the whip roll and the ratchet and pawl mechanism and operable to regulate the stroke of the pawl carrier in response to variations in the position of the whip roll under the tension of the warp.

5. A let-off for looms, comprising in combination, a warp beam, a shaft for rotat-

ing the warp beam extending to the front of the loom and adapted to be rotated manually from the front of the loom, means for rotating said shaft from a going portion of the loom including ratchet and pawl mechanism having a pawl carrier mounted for rocking movement to advance the pawl in a direction to rotate the ratchet, and means for rocking said pawl carrier, means supported for movement in response to variations in the tension of the warp, and connections between said means and said ratchet and pawl mechanism and operable to regulate the stroke of the pawl carrier in response to variations in the tension of the warp.

6. A let-off for looms having, in combination, a warp beam, a shaft for rotating said beam and extending from the beam to

the front of the loom and adapted to be rotated manually from the front of the loom, ratchet and pawl mechanism for turning said shaft and mounted at the front of the loom so that the pawl can be held manually out of engagement with the ratchet during the manual rotation of said shaft, a whip roll mounted for movement in response to variations in the tension of the warp, and connections between the whip roll and the ratchet and pawl driving mechanism for controlling the operation of the latter by the position of the whip roll under the tension of the warp.

In witness whereof I have signed my name to this specification.

JONAS NORTHROP.
